CLAIM

The ornamental design for a golf putting practice device, as shown and described.

DESCRIPTION

FIG. 1 is an illustrative view of a golf putting practice device showing the new design from the top;

FIG. 2 is a front view of the golf putting practice device of FIG. 1;

FIG. 3 is a rear view of the golf putting practice device of FIG. 1;

FIG. 4 is a bottom view of the golf putting practice device of FIG. 1;

FIG. 5 is a left side view of the golf putting practice device of FIG. 1; and,

FIG. 6 is a right side view of the golf putting practice device of FIG. 1.

The broken line showing is included for the purpose of illustrating and forms no part of the claimed design.
